[57] **CLAIM**

The ornamental design for a computer pedestal, as shown and described.

DESCRIPTION

FIG. 1 is a perspective view of a computer pedestal showing my new design; the broken line showing of a base stand and computer is for illustrative purposes only and forms no part of the claimed design;

FIG. 2 is a top plan view thereof;

FIG. 3 is a front elevational view thereof;

FIG. 4 is a left side elevational view as seen when in use, the right side being a mirror image thereof;

FIG. 5 is a rear elevational view thereof; and,

FIG. 6 is a bottom plan view thereof.

1 Claim, 2 Drawing Sheets
